UNITED STATES PATENT OFFICE.

CLARENCE D. PLATT, OF BRIDGEPORT, CONNECTICUT.

ELECTRIC SWITCH.

1,152,758.

Specification of Letters Patent.

Patented Sept. 7, 1915.

Application filed January 4, 1915. Serial No. 477.

To all whom it may concern:

Be it known that I, CLARENCE D. PLATT, a citizen of the United States of America, and residing at Bridgeport, in the county of 5 Fairfield and State of Connecticut, have invented new and useful Improvements in Electric Switches, of which the following is a specification.

My present invention relates particularly 10 to insulating covers for push button switches.

Special objects of the invention are to provide a simple, inexpensive device of this character which will be durable and 15 unlikely to become torn and injured.

Other objects are to facilitate the attachment of the cover to the body of the switch and to firmly secure the cover when attached in place so as to reduce the possibility 20 of detachment and loss of the cover either in shipment or handling.

In its simplest form the invention consists of a relatively flat sheet of insulating material having a straight sided slot therein 25 slightly wider than the narrower portion of the yoke which bridges the open side of the switch base. The edge portions bordering the said slot are preferably depressed below the plane of the sheet and engaged beneath 30 the wider portions of the yoke. As the slot need be merely the width of the narrower portion of the yoke, the cover is not materially weakened thereby and the absence of projecting fingers or the like practically 35 eliminates the possibility of tearing or injuring the cover by careless handling of the same.

The narrower portion of the supporting 40 yoke is usually located at an intermediate point approximately midway between its ends and with portions at each side thereof widened where the push buttons pass through the yoke. The depressed edge portions of the cover in engaging beneath these 45 widened portions thus secure the cover at two relatively widely separated points and so hold it the more firmly in place and prevent lateral shifting thereof. Shifting of the cover is furthermore prevented in the 50 preferred construction by means of the engagement of the edge portions of the slot with switch mechanism supporting arms dependent from opposite sides of the narrower intermediate portion of the yoke. The abut- 55 ment of these edges with the dependent arms

helps to center the cover and to prevent accidental disengagement thereof from the yoke.

In the accompanying drawing I have illustrated two of the preferred forms of my invention but I would have it understood 60 that modifications may be made therein without departing from the true spirit and scope of the invention.

Figure 1 is a perspective view of one form 65 of the cover applied to a push button switch of my own invention. Fig. 2 is a perspective view of the cover detached. Fig. 3, is a plan view of a slight modification of the cover.

7 designates the hollow insulating body of 70 the switch, constructed usually of porcelain and supported in proper position in the outlet box or the like by a yoke 8 which bridges the open front of the body and has projecting apertured ends 9 through which 75 the supporting screws are passed. This yoke may be secured to the body by screws 10 passed through from the back of the same.

The supporting yoke, in the intermediate 80 portion thereof substantially midway between its ends is relatively narrow, as indicated at 11 and at each side of this narrow portion it is widened or enlarged as indicated at 12 and apertured for the passage therethrough of the push buttons 13. Dependent 85 from the opposite edges of the narrow intermediate portion of the yoke are the arms 14, which in the illustration support the movable parts of the switch mechanism (not shown).

90 The insulating cover is designated 20. This cover consists of a relatively thin, flat plate or sheet of somewhat flexible and resilient insulating material such as fiber, of a size to close the open end of the switch body and provided with a longitudinal slot 95 21 therein slightly wider than the narrower portion of the yoke, narrower than the wider portions of the yoke and long enough to receive the wider portions of the yoke. The opposite edges of this slot are substantially straight and parallel and portions 22 of the said edges are preferably permanently offset or depressed below the substantially flat plane of the sheet.

100 The cover is usually applied by sliding it laterally to first engage the depressed portions bordering one edge of the slot in beneath the widened portions at that edge of the yoke, then bending or bowing the sheet 105 110

to turn the depressed portions at the opposite edge of the slot into position to pass beneath the widened portions of the yoke and simultaneously lowering such portions 5 to carry them down beneath the widened or bulged portions at the opposite edge of the yoke. When the depressed portions are thus engaged beneath the enlargements of the yoke the cover is firmly secured thereto 10 and positively held against accidental detachment. Lateral shifting of the cover is limited by the side edges of the slot abutting against the dependent switch-supporting arms 14 and the engagement of the 15 walls 23 at the back of the depressed portions with the edges of the yoke enlargements further serves to center and hold the cover in proper position. Twisting or rotative shifting of the cover is prevented by its 20 being held by the spaced enlargements at two relatively widely separated points. After the switch is installed in its outlet box the face plate or wall plate (not shown) covering the parts is applied in the 25 usual way.

In the modification illustrated in Fig. 3 the cover 30 is the same in general respects as the one just described except that the slot is not a continuous one, it being interrupted at an intermediate point by a cross strap 31, which when the cover is applied overlies and covers the narrow intermediate portion 11 of the yoke.

32 designates the depressed edge portions 35 which in this case also engage beneath the enlargements on the yoke.

What I claim is:—

1. The combination with an open switch body and a supporting yoke bridging the 40 open end of the same having a relatively narrow intermediate portion and enlargements at opposite sides of the same, of a sheet of insulating material covering the open end of the switch body, having a parallel sided slot therein as wide as the narrower intermediate portion and narrower than the enlarged portions of the yoke and edge portions bordering said slot engaged beneath the enlargements of the yoke.
2. The combination with a supporting 50 yoke provided with widened portions joined by a relatively narrower portion having

supporting arms dependent from the opposite edges thereof, of a relatively flat sheet of insulating material having a parallel sided slot therein of the width of the narrower portion of the yoke and portions bordering said slot depressed below the plane of the sheet, the said depressed edge portions being engaged beneath the wider portions of the yoke and the edges between the said engaging portions abutting the dependent arms of the yoke to thereby center the sheet in locked engagement with the yoke. 65

3. As an article of manufacture, a cover for push button switches comprising a resilient sheet of insulating material having a parallel sided slot therein, and edge portions bordering said slot adjacent the ends 70 thereof permanently depressed below the plane of the sheet.

4. The combination with an open switch body and a yoke bridging the open face of the same perforated for the passage of 75 switch push buttons therethrough, of an insulating cover for the switch consisting of a sheet of insulating material overlying the yoke at its ends and having a slot therein 80 extending between said ends and receiving the switch push buttons, said cover having flanges engaging beneath the edges of the yoke at relatively widely separated points adjacent opposite ends of the cover. 85

5. The combination with an open switch body and a yoke bridging the open face of the same provided with longitudinally separated portions perforated for the passage 90 of switch push buttons therethrough, of an insulating cover for the switch consisting of a sheet of insulating material overlying the yoke at its ends and having a slot therein 95 extending between said ends, said cover having flanges at the edges of the slot therein extending from the end portions which overlie the yoke down beneath the edges of the separated perforated portions of the yoke through which the push buttons pass whereby the cover is held down at four points adjacent the corners of the slot.

CLARENCE D. PLATT.
